FIG-1

FIG-2

FIGURE 1 is a front, left side and top perspective view of a television camera showing my new design; and

FIGURE 2 is a rear, right side and top perspective view of the camera of FIGURE 1, the bottom being conventionally plain.

The dominant features of my new design are shown in solid lines in the drawing.

Portions of FIGURE 1 are stippled to indicate contrast in appearances.

I claim:

The ornamental design for a television camera, substantially as shown and described.
